UNITED STATES PATENT OFFICE

2,590,464

AIRPLANE HANGAR

Antonin Raymond, New York, N. Y., assignor to
 National Steel Corporation, a corporation of
 Delaware

Application March 2, 1946, Serial No. 651,532

7 Claims. (Cl. 189—1.5)

1

This invention relates generally to buildings and more particularly to aircraft hangars.

It is an object of the invention to provide an arch rib building including a large doorway in an arched side wall of the building.

Another object of the invention resides in the relative arrangement of the building structure in a building of the above mentioned character.

Another object of the present invention is to provide an arch rib building of new and improved construction adapted to embody an overhead door closing a large doorway in the arched wall.

Another object of the invention is to provide a new and improved door for closing an opening in the side wall of an arched roof building.

Other objects of the invention will become apparent from the following detailed description taken in connection with the accompanying drawings in which:

Figure 1 is an isometric view of a building embodying features of the present invention;

Figure 2 is a fragmentary isometric view of one end of the building framework; and

Figure 3 is a cross-sectional view of the building.

In the drawings, which illustrate a preferred embodiment of the invention, the building shown comprises in general, a foundation 10, spaced end walls 11 and an arched roof-side wall structure 12. The lower, arcuate portions of the structure 12, designated generally by the numerals 13, 14 are hereinafter referred to as side walls although they are continuations both in contour and construction of the arched roof. The end walls 11 and the side wall 13 seat on the foundation 10 which may be a suitably wide concrete slab extending along and beneath these walls. This foundation is preferably partially embedded in the ground and anchored by suitable concrete footings 15. In the building side wall 14 there is a large doorway 16 to accommodate large vehicles, such as airplanes, the doorway 16 extending in width preferably substantially the entire length of the building. This doorway 16 is closable by a single overhead door, designated generally by the numeral 17.

The arched roof and side wall structure 12 includes a plurality of spaced, laterally positioned arched ribs 18 connected together by purlins 19 extending transversely of the ribs. The lower corresponding ends of the ribs 18 of the side wall 13 seat in and are secured to foundation plates or channels 20 which in turn may be secured or anchored to the foundation 10 by any suitable means. The other corresponding ends of the

2

ribs 18 terminate adjacent the top of the doorway 16 where they are connected together by a door frame header 21 which extends the full width of the doorway. The door frame header 21 is preferably of general channel form to receive therein, end portions of the ribs 18 which are preferably welded to the header. The roof and side wall structure 12 may be covered by any suitable sheathing material, preferably steel sheets arranged in overlapping relation, spanning preferably three or more of the ribs to add rigidity to the framing and to reduce the number of purlins required.

The building end walls 11 are preferably of like construction, each comprising, an end, arched rib 18, a foundation plate 22, a plurality of studs 23 and suitable exterior sheathing. The studs 23 have their lower ends seated on and secured to the foundation plate 22 which in turn is secured or anchored to the foundation 10. The upper ends of the studs 23 may be welded or be otherwise suitably secured to the end wall rib 18 and the exterior sheathing may be suitably secured to the end wall framework.

The doorway frame includes opposite side frame members 25 which aid in supporting the door header 21. These side, frame members 25 may have their upper ends welded respectively to opposite ends of the header 21 and the lower ends of the doorway side frame member 25 may be welded or be otherwise suitably secured to the end wall foundation plates 22. As shown, the doorway side frame members 25 are angularly disposed extending downwardly and inwardly from the door header 21 to the foundation plates 22. Similarly angularly disposed, an end wall stud 26 has its upper end secured to the end of the end wall rib, adjacent the door header 21 and has its lower end secured to the foundation plate of the end wall. Each of the end walls is further reinforced by a short stud 27 which is secured, preferably by welding at its upper end to the end wall rib 18, and is secured at its lower end to and intermediate the ends of the angularly disposed stud 26. At opposite sides of the doorway, the end wall sheathing may be brought around spanning the angularly disposed studs and the similarly angularly disposed side frame members 25 of the doorway framing as at 28, Figure 1.

Within the building, intermediate the doorway frame and the roof crown, a reinforcing or truss structure 30 is provided to strengthen the building in the vicinity of the doorway. The truss 30 is supported by a pair of spaced columns 31

located within the building respectively at or adjacent to the building end walls 11. Lower portions of the columns 31 preferably are embedded in concrete footings 33, partially sunk in the ground. The truss 30 comprises a plurality of frame members including a lower beam 34 and an upper beam 35 connected and mutually reinforced by struts 37. The struts 37 may have their opposite ends respectively secured, preferably by welding, to the beams 34, 35. These beams 34, 35 extend in substantially horizontal parallel relation throughout the length of the building, transversely to and supporting the ribs 18. The opposite ends of the lower beam 34 and the upper beam 35 are rigidly secured, preferably by welding to the columns 31 adjacent the upper ends thereof. The ribs 18 rest on the upper beam 35, preferably being welded thereto to provide a strong rigid frame construction. A beam 36 is disposed forwardly of the truss 30, extending parallel with the truss beams 34, 35. The beam 36 supports and ties the ribs together at points intermediate the upper beam 35 and the door header 21, the beam 36 preferably being located substantially in the same horizontal plane with the lower truss beam 34 as seen in Figure 3 of the drawings. This beam 36 is supported and reinforced along its length by spaced horizontal connecting members 38 which rigidly connect the beams 36 to the lower beam 34 of the truss 30. Opposite ends of the reinforcing connecting members 38 may be welded respectively to the beams 34 and 36. Preferably the truss supporting columns 31 are additionally supported by tie rods 40 located respectively adjacent the opposite end walls 11 of the building and anchored to the concrete footings 15.

The door 17 has a framework including a plurality of laterally spaced, arcuate ribs 42 of the same general contour or curvature as the roof ribs 18. These door ribs 42 may be rigidly connected together by top and bottom horizontal door frame members 43, 44 respectively, preferably channel members fitting over and welded to the ends of the ribs. At opposite ends of the door are triangular frame members each comprising an upright side frame member 45, a right angle or bottom frame member 46 and a connecting frame member 47. These frame members 45, 46, 47 are rigidly secured together at the corners by connecting plates 48 welded thereto. At each end of the door the upright frame member 45 constitutes the chord of the end door rib 42, being rigidly secured to the top and bottom door frame members 43, 44 preferably by welding. These triangular frames together with the end arcuate door ribs 42 form the end wall framing of the door. Metallic sheets 50 or other suitable sheathing may be used as an external covering for the end frames and also for covering the door ribs 42. The slope of the frame members 47 is preferably substantially the same as the corresponding slope of the door side frame member 25 to align therewith when the door is in closed position.

Within and at each end of the building, a stanchion 51 is provided, extending upwardly in spaced relation to the adjacent column 31, a lower end portion of the stanchion 51 being embedded in the concrete footing 33. At its upper end, each of the stanchions 51 is preferably, rigidly secured to the parallel, adjacent column 31 by a pair of connecting plates 52 welded or otherwise secured thereto. Below these plates 52, the stanchion 51 and the column 31 have aligning apertures to support a horizontal shaft 75

53. Pivoted on each of these shafts 53 there is a door operating lever 54 having a forwardly extending arm 55 positioned inside the end walls of the door 17. The outer ends of the lever arms 54 are secured, preferably by welding, to the ends of a truss cross frame member 56. The cross frame member 56 extends between and parallel with the top and bottom door frame members 43, 44 also connecting the door ribs 42 together, thus adding to the structural rigidity of the door frame. Inwardly of and substantially parallel with the cross frame member 56 is a second, truss cross member 57 connected therewith by laterally extending connecting members 58 to provide a rigid truss structure, connecting and reinforcing the door and door operating levers. This cross member 57, like the upper cross member 56, may have its ends welded to the pair of door operating levers 54, the cross member 57 adjacent its opposite ends preferably being secured by corner brace plates 59 to the lever arms 55 for added rigidity. On the opposite ends of each of the door operating levers 54, a suitable counter balance 60 is provided acting to swing the door upwardly about the fulcrums of the levers 54.

I claim:

1. In a building, the combination comprising, a plurality of spaced laterally positioned arched ribs, the ribs having corresponding ends thereof terminating adjacent the top of a doorway, a truss extending transversely of and supporting the ribs intermediate the rib crowns and the said corresponding ends thereof, a beam extending transversely of and supporting the ribs intermediate the truss and the said corresponding ends of the ribs, and members connecting together the truss and beam.

2. In a building, the combination comprising, a plurality of spaced laterally positioned arched ribs, the ribs having corresponding ends thereof terminating adjacent the top of a doorway, a truss extending transversely of and supporting the ribs intermediate the rib crowns and the said corresponding ends thereof, a beam supported by the truss extending transversely of and supporting the ribs intermediate the first truss and the said corresponding ends of the ribs, the truss and beam being connected to the ribs.

3. In a building, the combination comprising, a plurality of spaced laterally positioned arched ribs, the ribs having corresponding ends thereof terminating adjacent the top of a doorway, a truss including an upper beam and a lower beam extending transversely of and supporting the ribs intermediate the rib crowns and the said terminal ends thereof, a third beam extending transversely of and supporting the ribs intermediate the first truss and the said terminal ends of the ribs, the lower beam of the truss and the third beam being in substantially the same horizontal plane and the upper beam of the truss and the third beam being connected to the ribs, and means interconnecting the lower beam and the third beam.

4. In a building, the combination comprising, a plurality of laterally spaced arched ribs, the ribs having corresponding ends thereof terminating adjacent the top of a doorway, a truss extending transversely beneath and supporting the ribs intermediate the rib crowns and the said terminal ends thereof, means supporting the ends of the truss, and an overhead door closing the doorway and pivotally connected to the truss supporting means and arranged to swing in an arc beneath the truss.

5. In a building, the combination comprising, a plurality of laterally spaced arched ribs, the ribs having corresponding ends thereof terminating adjacent the top of a doorway, a truss extending transversely beneath and supporting the ribs intermediate the rib crowns and the said terminal ends thereof, a beam supported by the truss extending transversely beneath and supporting the ribs intermediate the truss and the said terminal ends of the ribs, a pair of spaced columns supporting the truss and the beam, and an overhead door closing the doorway pivotally connected to the pair of spaced columns for swinging movement through an arc below the truss and beam.

6. In a building, the combination comprising, a plurality of laterally spaced arched ribs, the ribs having corresponding ends thereof terminating adjacent the top of a doorway, a truss extending transversely of and supporting the ribs intermediate the rib crowns and the said corresponding ends thereof, columns disposed adjacent opposite sides of the doorway supporting the truss, an overhead door closing the doorway and arranged to swing through an arc immediately beneath the truss, and door operating arms pivoted on the columns carrying the door.

7. In a building, the combination comprising, a roof and side wall structure including a plurality of laterally spaced arched ribs, the ribs having corresponding ends terminating substantially at the top of a doorway in one of the side walls, end wall framing including the end ribs and a pair of framing members respectively supporting the said

terminating ends of the end ribs extending downwardly and inwardly therefrom, a door header member extending transversely of and connecting the ribs together at the said terminal ends thereof, doorway side frame members supporting the header intermediate the pair of framing members, the doorway side frame members extending downwardly and inwardly from the header at substantially the same angularity as the pair of framing members, and a truss extending transversely beneath and supporting the ribs intermediate the rib crowns and the said terminal ends of the ribs.
